WALL PAPER.

No. 15,245.

Patented Aug. 12, 1884.

UNITED STATES PATENT OFFICE.

ALBERT LEISEL, OF NEW YORK, N. Y.

DESIGN FOR WALL-PAPER.

SPECIFICATION forming part of Design No. 15,245, dated August 12, 1884.

Application filed April 11, 1884. Term of patent 3½ years.

To all whom it may concern:

Be it known that I, ALBERT LEISEL, a citizen of the Empire of Germany, residing in the city of New York, county and State of New York, have invented and produced a new and original Design for Wall or Ceiling Covering, which is especially intended as a wall-hanging or ceiling-filling.

The drawing represents a front plan view of the design.

This design is in the Renaissance style; and it consists of a radiating-star-like figure having as a center a small rosette, *a*. From this issue scrolls *b*, with volutes forming a square. Around the latter are grouped crescent-shaped scrolls, *c*, terminating at one end by a volute, and with leaflets at the other extremity. These scrolls are tied by an astragal. Between the volutes of the scrolls are placed expanding leaf-buds *e*, between which are arranged shells *f*, the surfaces of which are escalloped.

The details so far described form one symmetrical figure, the interstices being filled in by a finely-beaded ground, and is inclosed by a border consisting of semi-circles *g* connected by right angles. This border is shaded with fine-line work.

The intermediate spaces of the design are occupied by a figure having for its center a rosette, *h*, surrounded by a wreath of leaf-scrolls, *i*. At the four sides of this wreath are placed two leaf-scrolls, *k*, between the volutes of which is arranged an ornament, *l*. Springing from the four oblique angles of the wreath a stem surmounted by a trifoliate flower, *m*, is seen, the latter overlapping the border mentioned in the first part of this description.

The interstices of the whole of this design are filled in with a granulated groundwork, that around the first device being of a coarser nature than that used around the second. The borders mentioned as inclosing the first device are joined by a star consisting of four leaflets with a center button.

I claim—

The design for a wall or ceiling covering, shown in the print accompanying this description.

ALBERT LEISEL.

Witnesses:

PHILLIPS ABBOTT,
JOHN MICHELS.
